DIE CASTING MACHINE

CROSS-REFERENCE TO RELATED APPLICATION

This application is continuation application of, and claims the benefit of priority from the International Application PCT/JP2020/18375, filed May 1, 2020, which claims the benefit of priority from Japanese Patent Application No. 2019-094042, filed on May 17, 2019, the entire contents of all of which are incorporated herein by reference.

FIELD OF THE INVENTION

The present invention relates to a die casting machine and particularly to a semi-hot chamber type die casting machine.

BACKGROUND OF THE INVENTION

In a so-called semi-hot chamber type die casting machine, a sleeve connected to an inside of a mold and a plunger extruding molten metal in the sleeve into the mold are provided outside a holding furnace storing molten metal similarly to a cold chamber type die casting machine. However, in the semi-hot chamber type, the holding furnace and the sleeve are connected to each other and molten metal is supplied to the sleeve via a molten metal supply pipe connected to the sleeve instead of pumping the molten metal in the holding furnace by the ladle and pouring the molten metal into the sleeve unlike the cold chamber type.

In the semi-hot chamber type die casting machine, there is concern that an impact is applied to a connection portion between the sleeve and the molten metal supply pipe during the injection of the plunger so that the molten metal supply pipe may be broken. Thus, it is desired to reduce the impact applied to the molten metal supply pipe during the injection of the plunger and suppress the breakage of the molten metal supply pipe.

SUMMARY OF THE INVENTION

A die casting machine according to an aspect of the invention includes: a holding furnace holding molten metal; a sleeve located outside the holding furnace, the sleeve connected to an inside of a mold, and the sleeve having a molten metal supply port; a plunger sliding through the sleeve and including a plunger rod and a plunger tip fixed to a tip of the plunger rod; a molten metal supply pipe pushed against the sleeve to cover the molten metal supply port and supplying the molten metal into the sleeve; and a pushing force variable mechanism configured to reduce a pushing force of the molten metal supply pipe against the sleeve when the plunger is sliding.

The die casting machine of the above-described aspect may further include a pushing force control circuit configured to reduce the pushing force by controlling the pushing force variable mechanism after the plunger tip blocks the molten metal supply port.

In the die casting machine of the above-described aspect, the molten metal supply port may be provided at a lower portion of the sleeve.

In the die casting machine of the above-described aspect, the molten metal supply pipe may be fixed to the holding furnace and the pushing force variable mechanism may change a force applied to the holding furnace.

In the die casting machine of the above-described aspect, the molten metal supply pipe may be movable relative to the

2

holding furnace and the pushing force variable mechanism may change a force applied to the molten metal supply pipe independently from the holding furnace.

In the die casting machine of the above-described aspect, the molten metal supply pipe may have a cylindrical shape extending in a linear shape.

In the die casting machine of the above-described aspect, the molten metal supply pipe may be made of ceramics.

The die casting machine of the above-described aspect may further include a molten metal supply drive device configured to generate a driving force for transferring the molten metal from the holding furnace to the sleeve via the molten metal supply pipe.

In the die casting machine of the above-described aspect, the molten metal supply drive device may be an electromagnetic pump.

In the die casting machine of the above-described aspect, the molten metal supply drive device may be a pneumatic device raising an air pressure in the holding furnace.

The die casting machine of the above-described aspect may further include a molten metal supply control circuit configured to control the molten metal supply drive device so that a filling rate of the molten metal in the sleeve at a time point when the supply of the molten metal into the sleeve is completed becomes 70% or more.

In the die casting machine of the above-described aspect, the molten metal supply control circuit may control the molten metal supply drive device so that the filling rate of the molten metal in the sleeve when the plunger tip reaches a position of blocking the molten metal supply port becomes 95% or more.

The die casting machine of the above-described aspect may further include a first sensor facing a predetermined height between a lowermost portion and an uppermost portion of an inner surface of the sleeve and detecting that the molten metal in the sleeve reaches the predetermined height.

In the die casting machine of the above-described aspect, the sleeve may include a gas vent port provided at an upper portion, and the die casting machine may further include a second sensor provided above the gas vent port and detecting a molten metal surface position of the molten metal in the sleeve.

The die casting machine of the above-described aspect may further include an injection drive device configured to drive the plunger and an injection control circuit configured to control the injection drive device so that an injection speed of the plunger increases after the plunger tip reaches a position of blocking the molten metal supply port.

BRIEF DESCRIPTION OF THE DRAWINGS

FIG. 1 is a schematic view showing an overall configuration of a die casting machine of a first embodiment.

FIG. 2 is a schematic cross-sectional view showing a sleeve, a plunger, and a molten metal supply device of the die casting machine of the first embodiment.

FIG. 3 is a schematic cross-sectional view of a sleeve and a molten metal supply pipe of the die casting machine of the first embodiment.

FIG. 4 is a block diagram showing a configuration of a signal processing system of the die casting machine of the first embodiment.

FIG. 5 is a flowchart of an example of an operation of the die casting machine of the first embodiment.

FIG. 6 is an explanatory diagram of an example of an operation of the die casting machine of the first embodiment.

FIGS. 7A, 7B, and 7C are an explanatory diagram of an example of an operation of the die casting machine of the first embodiment.

FIG. 8 is a schematic cross-sectional view showing a sleeve, a plunger, and a molten metal supply device of a die casting machine of a second embodiment.

FIG. 9 is a schematic cross-sectional view showing a sleeve, a plunger, and a molten metal supply device of a die casting machine of a third embodiment.

FIG. 10 is a schematic cross-sectional view showing a sleeve, a plunger, and a molten metal supply device of a die casting machine of a fourth embodiment.

DETAILED DESCRIPTION OF THE EMBODIMENTS

Hereinafter, embodiments of the invention will be described with reference to the drawings.

First Embodiment

A die casting machine of a first embodiment includes: a holding furnace holding molten metal; a sleeve located outside the holding furnace, the sleeve connected to an inside of a mold, and the sleeve having a molten metal supply port; a plunger sliding through the sleeve and including a plunger rod and a plunger tip fixed to a tip of the plunger rod; a molten metal supply pipe pushed against the sleeve to cover the molten metal supply port and supplying the molten metal into the sleeve; and a pushing force variable mechanism reducing a pushing force of the molten metal supply pipe against the sleeve when the plunger is sliding.

FIG. 1 is a schematic view showing an overall configuration of the die casting machine of the first embodiment. FIG. 1 is a side view including a partially cross-sectional view. FIG. 2 is a schematic cross-sectional view showing the sleeve, the plunger, and the molten metal supply device of the die casting machine of the first embodiment.

FIG. 3 is a schematic cross-sectional view of the sleeve and the molten metal supply pipe of the die casting machine of the first embodiment. FIG. 3 is a cross-sectional view perpendicular to the extension direction of the sleeve. Additionally, the up and down direction of the paper is the vertical direction and the left and right direction of the paper and the penetration direction of the paper are the horizontal directions.

FIG. 4 is a block diagram showing a configuration of a signal processing system of the die casting machine of the first embodiment.

A die casting machine 100 of the first embodiment is a semi-hot chamber type die casting machine.

The die casting machine 100 includes a mold clamping device 10, an extrusion device 12, an injection device 14, a mold 16, a control system 18, and a molten metal supply device 20.

The injection device 14 includes a sleeve 22, a plunger 24, an injection drive device 25, and a position sensor 27. The plunger 24 includes a plunger tip 24a and a plunger rod 24b. The sleeve 22 is provided with a molten metal sensor 26 (first sensor), a molten metal supply port 28, and a gas vent port 30.

The mold 16 includes a fixed die 16a and a movable die 16b.

The control system 18 includes a control device 32, an input device 34, and a display device 36. The control device 32 includes a molding condition setting circuit 32a, a molten

metal supply control circuit 32b, an injection control circuit 32c, and a pushing force control circuit 32d.

The molten metal supply device 20 includes a molten metal supply pipe 40, a holding furnace 42, a packing 44, a first heater 46, a guard member 48, a molten metal supply pipe sleeve 50, a second heater 52, an electromagnetic pump (molten metal supply drive device), a molten metal level sensor 56 (second sensor), a fulcrum 62, a metal feeder 64, an actuator 90 (pushing force variable mechanism), an elastic body 92, a push-up member 94, a load sensor 96, and a stopper 98. The holding furnace 42 is provided with a holding furnace molten metal level sensor 66, a filter 68, a filter support 70, a holding furnace heater 72, and a metal supply port 74. The electromagnetic pump 54 includes a coil 54a and a core 54b.

The die casting machine 100 is a machine that manufactures a die casting product by injecting a liquid metal (molten metal) into the mold 16 (cavity Ca in FIG. 1) and solidifying the liquid metal in the mold 16. The metal is, for example, aluminum, an aluminum alloy, a zinc alloy, or a magnesium alloy.

The mold 16 is provided between the mold clamping device 10 and the injection device 14. The mold 16 includes the fixed die 16a and the movable die 16b.

The mold clamping device 10 has a function of opening and closing the mold 16 and clamping the mold.

The injection device 14 has a function of injecting a liquid metal into the mold 16. The injection device 14 includes, as shown in FIG. 1, the sleeve 22, the plunger 24, the injection drive device 25, and the position sensor 27.

The sleeve 22 is located outside the holding furnace 42 that holds the molten metal. The sleeve 22 passes through the mold 16. The sleeve 22 is, for example, a tubular member connected to the fixed die 16a. The sleeve 22 has, for example, a cylindrical shape.

The plunger 24 slides through the sleeve 22. The plunger tip 24a fixed to the tip of the plunger rod 24b slides through the sleeve 22 in the front and rear direction. Since the plunger tip 24a slides forward through the sleeve 22, the molten metal in the sleeve 22 is extruded into the mold 16.

The injection drive device 25 has a function of driving the plunger 24 in the front and rear direction. The injection drive device 25 is, for example, a hydraulic type, an electric type, or a hybrid type in which a hydraulic type and an electric type are combined.

The position sensor 27 has a function of detecting the position of the plunger 24. The position sensor 27 is, for example, an optical or magnetic linear encoder. It is possible to detect the speed of the plunger 24 by differentiating the position of the plunger 24 detected by the position sensor 27.

As shown in FIG. 3, the sleeve 22 is provided with the molten metal sensor 26 (first sensor), the molten metal supply port 28, and the gas vent port 30.

The molten metal supply port 28 is provided at the lower portion of the sleeve 22. The molten metal is supplied from the molten metal supply pipe 40 connected to the molten metal supply port 28 into the sleeve 22.

The gas vent port 30 is provided at the upper portion of the sleeve 22. The gas vent port 30 has a function of exhausting the gas in the upper portion of the sleeve 22 when the sleeve 22 is filled with the molten metal. The filling time of the molten metal in the sleeve 22 is shortened by providing the gas vent port 30.

The molten metal sensor 26 faces a predetermined height between the lowermost portion and the uppermost portion of the inner surface of the sleeve 22. The molten metal sensor 26 is exposed into, for example, the sleeve 22.

The molten metal sensor 26 detects that the molten metal reaches the position of the molten metal sensor 26 in the sleeve 22.

The molten metal sensor 26 is, for example, a resistance sensor having a pair of electrodes and outputting a signal by energizing when the molten metal reaches the position of the electrodes. Further, the molten metal sensor 26 is, for example, a temperature sensor that outputs a signal when the temperature exceeds a predetermined value. Further, the molten metal sensor 26 is, for example, a pressure sensor that outputs a signal when the pressure exceeds a predetermined value.

The molten metal supply device 20 is provided below the sleeve 22. The molten metal supply device 20 has a function of supplying the molten metal into the sleeve 22 and filling the sleeve 22 with the molten metal.

The molten metal supply device 20 includes the molten metal supply pipe 40, the holding furnace 42, the packing 44, the first heater 46, the guard member 48, the molten metal supply pipe sleeve 50, the second heater 52, the electromagnetic pump 54 (molten metal supply drive device), the molten metal level sensor 56 (second sensor), the fulcrum 62, the metal feeder 64, the actuator 90 (pushing force variable mechanism), the elastic body 92, the push-up member 94, the load sensor 96, and the stopper 98.

The molten metal supply pipe 40 is provided below the sleeve 22. One end of the molten metal supply pipe 40 is pushed against the sleeve 22 to cover the molten metal supply port 28. The molten metal supply pipe 40 contacts the sleeve 22 so that the center axis of the molten metal supply pipe 40 is aligned to the center axis of the molten metal supply port 28.

A pushing force of the molten metal supply pipe 40 with respect to the sleeve 22 is variable. The pushing force of the molten metal supply pipe 40 with respect to the sleeve 22 is adjusted by the actuator 90. The molten metal supply pipe 40 is fixed to, for example, the holding furnace 42. The molten metal supply pipe 40 has a function of supplying the molten metal into the sleeve 22.

The molten metal supply pipe 40 is a tubular member. The molten metal supply pipe 40 has, for example, a cylindrical shape extending in a linear shape in the vertical direction. For example, the diameter of the cylinder may change in the vertical direction. The molten metal supply pipe 40 does not include, for example, a bent portion.

The molten metal supply pipe 40 is made of, for example, ceramics. The molten metal supply pipe 40 is made of, for example, only ceramics.

The packing 44 is provided at the upper end of the molten metal supply pipe 40. The packing 44 has a function of preventing the molten metal from leaking from a gap of the contact portion between the sleeve 22 and the molten metal supply pipe 40. The packing 44 has heat resistance.

The first heater 46 is provided around the molten metal supply pipe 40. The first heater 46 has a function of heating the molten metal in the molten metal supply pipe 40.

The guard member 48 covers the upper end portion and the upper portion side surface of the first heater 46. The guard member 48 has a function of protecting the first heater 46.

The molten metal supply pipe sleeve 50 is provided below the molten metal supply pipe 40. The lower end of the molten metal supply pipe 40 is inserted into, for example, the molten metal supply pipe sleeve 50. The lower end of the molten metal supply pipe sleeve 50 is immersed into the molten metal of the holding furnace 42. The molten metal supply pipe sleeve 50 is made of, for example, ceramics.

The second heater 52 is provided in the molten metal supply pipe sleeve 50. The second heater 52 has a function of heating the molten metal in the molten metal supply pipe sleeve 50.

5 The electromagnetic pump 54 is an example of the molten metal supply drive device. The electromagnetic pump 54 includes the coil 54a and the core 54b. The coil 54a is provided around the molten metal supply pipe 40 and the core 54b is provided in the molten metal supply pipe 40.

10 The electromagnetic pump 54 generates a driving force for transferring the molten metal from the holding furnace 42 to the sleeve 22 via the molten metal supply pipe 40.

As shown in FIG. 3, the molten metal level sensor 56 is provided above the gas vent port 30 provided in the sleeve 22. The molten metal level sensor 56 has a function of detecting the molten metal surface position in the sleeve 22.

15 The molten metal level sensor 56 is, for example, a non-contact type sensor that detects the height of the molten metal surface from above the molten metal surface. The molten metal level sensor 56 is, for example, an optical or ultrasonic sensor.

The holding furnace 42 is provided below the sleeve 22. The holding furnace 42 has a function of holding the molten metal therein.

20 25 The holding furnace 42 is provided with the holding furnace molten metal level sensor 66, the filter 68, the filter support 70, the holding furnace heater 72, and the metal supply port 74.

The holding furnace molten metal level sensor 66 has a 30 function of detecting the position of the molten metal surface in the holding furnace 42. The holding furnace molten metal level sensor 66 is, for example, a non-contact type sensor that detects the height of the molten metal surface from above the molten metal surface. The holding furnace molten metal level sensor 66 is, for example, an optical or ultrasonic sensor.

35 For example, the height of the molten metal surface in the holding furnace 42 is maintained at a predetermined position by supplying an ingot into the holding furnace 42 based on the height of the molten metal surface detected by the holding furnace molten metal level sensor 66. For example, the molten metal surface in the molten metal supply pipe 40 is brought into contact with the core 54b of the electromagnetic pump 54 by maintaining the height of the molten metal surface in the holding furnace 42 at a predetermined position.

40 45 The filter 68 is provided in the holding furnace 42. The filter 68 suppresses the supply of solid matter such as oxides of the molten metal contained in the molten metal into the sleeve 22.

The filter support 70 is fixed to the filter 68. The filter support 70 has a function of pulling the filter 68 out of the holding furnace 42.

The holding furnace heater 72 is immersed in the molten metal in the holding furnace 42. The holding furnace heater 72 has a function of heating the molten metal in the holding furnace 42.

50 55 The metal supply port 74 is provided on the upper surface of the holding furnace 42. For example, an ingot that is a raw material for molten metal is input from the metal supply port 74. The molten metal may be supplied from the metal supply port 74.

60 65 The actuator 90 is provided below the side surface of the holding furnace 42. The actuator 90 is an example of a pushing force variable mechanism. The actuator 90 has a function of reducing a pushing force of the molten metal supply pipe 40 with respect to the sleeve 22 when the

plunger 24 is sliding. The actuator 90 applies a force of pushing down the holding furnace 42. The actuator 90 changes a force applied to the holding furnace 42.

The fulcrum 62 is provided below the holding furnace 42.

The elastic body 92 is provided below the side surface of the holding furnace 42. The elastic body 92 is provided on the side opposite to the actuator 90 with the fulcrum 62 interposed therebetween. The elastic body 92 has a function of pushing the molten metal supply pipe 40 against the sleeve 22. The elastic body 92 is, for example, a spring.

The push-up member 94 is fixed to the side surface of the holding furnace 42 and is provided above the elastic body 92. An upward force is applied to the push-up member 94 by the elastic body 92.

The load sensor 96 is provided above the push-up member 94. It is possible to monitor the pushing force of the molten metal supply pipe 40 with respect to the sleeve 22 by the load sensor 96.

The stopper 98 is provided above the push-up member 94. The stopper 98 limits the upward displacement of the push-up member 94 and suppresses the excessive pushing force of the molten metal supply pipe 40 with respect to the sleeve 22.

The metal feeder 64 is provided above the holding furnace 42. The metal feeder 64 supplies, for example, an ingot as a raw material for molten metal into the holding furnace 42 from the metal supply port 74. The metal feeder 64 may supply the molten metal from, for example, the metal supply port 74.

The control system 18 includes the control device 32, the input device 34, and the display device 36.

The input device 34 is provided on, for example, a fixed die plate (reference numeral omitted) of the mold clamping device 10. The input device 34 receives an operator's input operation. The operator can set the molding conditions and the like of the die casting machine 100 by using the input device 34.

The input device 34 is, for example, a touch panel using a liquid crystal display or an organic EL display.

The display device 36 is provided on, for example, the fixed die plate (reference numeral omitted) of the mold clamping device 10. The display device 36 displays, for example, the molding conditions, the operation status, and the like of the die casting machine 100 on the screen. The display device 36 is, for example, a liquid crystal display or an organic EL display.

The control device 32 has a function of controlling the molding operation of the die casting machine 100 using the mold clamping device 10, the extrusion device 12, the injection device 14, and the molten metal supply device 20. The control device 32 has a function of performing various calculations and outputting a control command to each part of the die casting machine 100.

The control device 32 has, for example, a combination of hardware and software. The control device 32 includes, for example, a CPU (Central Processing Unit), a semiconductor memory, and a control program stored in the semiconductor memory.

The control device 32 includes, as shown in FIG. 4, the molding condition setting circuit 32a, the molten metal supply control circuit 32b, the injection control circuit 32c, and the pushing force control circuit 32d.

The molding condition setting circuit 32a has a function of setting various molding conditions such as the injection speed of the plunger 24 based on the signal from the input device 34.

The molten metal supply control circuit 32b has a function of controlling the supply of the molten metal from the holding furnace 42 into the sleeve 22 based on the data of the molten metal surface position detected by the molten metal sensor 26 and the molten metal level sensor 56. The supply of the molten metal into the sleeve 22 is performed by controlling the driving of the electromagnetic pump 54.

The molten metal supply control circuit 32b controls the electromagnetic pump 54, for example, so that the filling rate of the molten metal in the sleeve 22 at the time point when the supply of the molten metal to the sleeve 22 is completed is 70% or more. Further, the molten metal supply control circuit 32b controls the electromagnetic pump 54, for example, so that the filling rate of the molten metal in the sleeve 22 when the plunger tip 24a reaches a position of blocking the molten metal supply port 28 becomes 95% or more.

The injection control circuit 32c has a function of controlling the injection drive device 25 based on the position of the plunger 24 detected by the position sensor 27. For example, the injection control circuit 32c controls the injection drive device 25 so that the injection speed of the plunger 24 increases after the plunger tip 24a reaches a position of blocking the molten metal supply port 28.

The pushing force control circuit 32d has a function of controlling the actuator 90 based on the position of the plunger 24 detected by the position sensor 27 and the load measured by the load sensor 96. For example, the pushing force control circuit 32d reduces the pushing force of the molten metal supply pipe 40 with respect to the sleeve 22 by controlling the actuator 90 after the plunger tip 24a blocks the molten metal supply port 28.

Next, an example of the operation of the die casting machine 100 will be described.

FIG. 5 is a flowchart of an example of the operation of the die casting machine of the first embodiment. FIG. 5 shows a period from the molten metal supply state into the sleeve 22 to the pressure raising and maintaining state after the high-speed injection. That is, the description of the mold closing and clamping operations before the molten metal supply state and the mold opening operation, the extrusion, and the like after the pressure raising and maintaining state will be omitted. The operation for which the description is omitted is, for example, the same as a known operation.

The operation of the die casting machine 100 includes a molten metal supply start step (Step ST1), a molten metal detection determination step (Step ST2), a deceleration start step (Step ST3), a molten metal supply stop step (Step ST4), an injection start step (Step ST5), a closed position determination step (Step ST6), a pushing force reduction step (Step ST7), a high-speed injection step (Step ST8), and a pressure raising and maintaining step (Step ST9).

FIGS. 6 7A, 7B, and 7C are explanatory diagrams of the operation of the die casting machine of the first embodiment.

FIG. 6 is a graph showing an example of an injection operation of the die casting machine 100. The horizontal axis indicates a time. As time goes by, the plotted points are on the left side of the paper. The vertical axis on the right side of the paper shows the injection speed, that is, the speed of the plunger 24. Further, the vertical axis on the left side of the paper shows the filling rate of the molten metal in the sleeve 22. The filling rate means the ratio of the molten metal to the volume of the sleeve 22 in front of the plunger 24. The line Lv indicates a change in the injection speed over time. Further, the line Lr indicates a change in the filling rate of the molten metal into the sleeve 22 over time.

FIGS. 7A, 7B, and 7C are a schematic diagram showing a state in the sleeve 22 during the injection operation of the die casting machine 100 of the first embodiment. FIG. 7A shows a case at the time t_0 , FIG. 7B shows a case at the time t_1 , and FIG. 7C shows a case at the time t_3 .

In Step ST1, when a predetermined molten metal supply start condition is satisfied, the supply of the molten metal into the sleeve 22 is started by the command from the molten metal supply control circuit 32b. Specifically, the electromagnetic pump 54 is operated to start the supply of the molten metal from the holding furnace 42 into the sleeve 22 via the molten metal supply pipe 40.

At the time point of Step ST1, the pushing force of the molten metal supply pipe 40 with respect to the sleeve 22 becomes the sum of the force f which is applied to the push-up member 94 by the elastic body 92 and the force F in which the actuator 90 pushes down the holding furnace 42.

For example, the pushing force control circuit 32d controls the pushing force of the molten metal supply pipe 40 with respect to the sleeve 22 so that the pushing force does not become excessive by feeding back the measurement value of the load sensor 96 to the force F in which the actuator 90 pushes down the holding furnace 42.

In Step ST2, the molten metal supply control circuit 32b determines whether or not the molten metal surface in the sleeve 22 reaches a predetermined height by the molten metal sensor 26. In the case of the negative determination, the molten metal supply control circuit 32b maintains the current molten metal supply speed. In the case of the positive determination, the molten metal supply control circuit 32b proceeds to the following Step ST3.

In Step ST3, the molten metal supply control circuit 32b controls the electromagnetic pump 54 so that the molten metal supply speed into the sleeve 22 decreases. It is possible to realize a desired filling rate with high accuracy by decreasing the molten metal supply speed.

In Step ST4, when a predetermined molten metal supply stop condition is satisfied, the molten metal supply control circuit 32b stops the supply of the molten metal from the holding furnace 42 to the sleeve 22. The molten metal supply stop condition is, for example, that the height of the molten metal surface detected by the molten metal level sensor 56 reaches a predetermined value satisfying a desired filling rate. The molten metal supply stop operation is performed by stopping the operation of the electromagnetic pump 54.

Step ST4 is a state of the time t_0 of FIG. 6. Further, Step ST4 is a state of FIG. 7A. The molten metal supply control circuit 32b controls the electromagnetic pump 54, for example, so that the filling rate of the molten metal M into the sleeve 22 becomes 70% or more. Also at the time point of Step ST4, the pushing force of the molten metal supply pipe 40 with respect to the sleeve 22 is the sum ($f+F$) of the force f which is applied to the push-up member 94 by the elastic body 92 and the force F in which the actuator 90 pushes down the holding furnace 42.

In Step ST5, the injection of the molten metal into the sleeve 22 starts by the command of the injection control circuit 32c. That is, injection drive device 25 is controlled so that the plunger 24 starts to advance. The injection speed of the plunger 24 at this time is relatively low between the time t_0 and the time t_1 in FIG. 6. The injection speed of the plunger 24 is, for example, less than 1 m/s.

In Step ST6, the injection control circuit 32c and the pushing force control circuit 32d determine whether or not the plunger 24 reaches a position of blocking the molten metal supply port 28 from the position information detected

by the position sensor 27. In the case of the negative determination, a relatively low injection speed is maintained. In the case of the positive determination, the process advances to Step ST7.

In Step ST7, the pushing force control circuit 32d reduces the pushing force of the molten metal supply pipe 40 with respect to the sleeve 22. Specifically, the pushing force control circuit 32d issues, for example, a command to the actuator 90 to stop an operation in which the actuator 90 pushes down the holding furnace 42. Since a force of pushing down the holding furnace 42 disappears, the pushing force of the molten metal supply pipe 40 with respect to the sleeve 22 only becomes the force f which is applied to the push-up member 94 by the elastic body 92.

Step ST7 is a state of the time t_1 of FIG. 6. Further, Step ST7 is a state of FIG. 7B. At this time, for example, the molten metal supply control circuit 32b maintains the molten metal surface position in the molten metal supply pipe 40 at a relatively high position directly below the molten metal supply port 28.

Since the molten metal supply port 28 is blocked by the plunger tip 24a, the molten metal M in the sleeve 22 does not leak from the molten metal supply port 28 even when the pushing force of the molten metal supply pipe 40 with respect to the sleeve 22 is reduced. The filling rate of the molten metal M in the sleeve 22 is, for example, 95% or more. The filling rate of the molten metal M in the sleeve 22 is, for example, 100%.

In Step ST8, the injection control circuit 32c increases the injection speed of the plunger 24. The injection control circuit 32c controls the injection drive device 25 to switch the injection speed of the plunger 24 to the high-speed injection speed VH for the high-speed injection. The injection speed of the plunger 24 is, for example, 1 m/s or more.

In Step ST9, the injection control circuit 32c controls the injection drive device 25 to raise and maintain the pressure of the molten metal M.

Step ST9 is a state of the time t_3 of FIG. 7C. Further, Step ST9 is a state of FIG. 7C. In Step ST9, the plunger 24 is stopped.

Steps ST1 to ST9 are performed every casting cycle.

Next, the function and effect of the die casting machine of the first embodiment will be described.

In the semi-hot chamber type die casting machine, the molten metal supply pipe may be broken due to an impact applied to the connection portion between the sleeve and the molten metal supply pipe during the injection of the plunger. Thus, it is desired to reduce the impact applied to the molten metal supply pipe during the injection of the plunger and suppress the breakage of the molten metal supply pipe.

The die casting machine 100 of the first embodiment includes the actuator 90 which reduces the pushing force of the molten metal supply pipe 40 with respect to the sleeve 22 when the plunger 24 is sliding. Since the pushing force of the molten metal supply pipe 40 with respect to the sleeve 22 is reduced, an impact applied to the molten metal supply pipe 40 is reduced with the injection of the plunger 24. Thus, the breakage of the molten metal supply pipe 40 is suppressed.

It is preferable to maintain the molten metal surface position in the molten metal supply pipe 40 at a relatively high position directly below the molten metal supply port 28 after reducing the pushing force of the molten metal supply pipe 40 with respect to the sleeve 22. Accordingly, it is possible to shorten the molten metal filling time to the sleeve 22 at the subsequent casting cycle.

11

The molten metal supply pipe 40 is preferably formed only of ceramics having high heat resistance. For example, when metal is used for the molten metal supply pipe 40, the molten metal supply pipe made of metal may be broken by the high-temperature molten metal. Ceramics are inferior in impact resistance to metals. However, in the die casting machine 100 of the first embodiment, since the pushing force of the molten metal supply pipe 40 with respect to the sleeve 22 is reduced, the impact applied to the molten metal supply pipe 40 is reduced. Thus, the molten metal supply pipe 40 can be formed only of ceramics.

The ceramic molten metal supply pipe 40 preferably does not have a bent portion from the viewpoint of maintaining strength. The molten metal supply pipe 40 preferably has a cylindrical shape extending in a linear shape from the viewpoint of maintaining strength.

The die casting machine 100 of the first embodiment includes the molten metal sensor 26 and the molten metal level sensor 56. The molten metal sensor 26 can detect the molten metal surface immediately before the supply of the molten metal ends and switch the molten metal supply speed from a high speed to a low speed. Then, the molten metal level sensor 56 can measure the molten metal surface position with high accuracy. Thus, it is possible to shorten the molten metal supply time and improve the molten metal supply accuracy.

The molten metal supply control circuit 32b controls the electromagnetic pump 54 so that the filling rate of the molten metal in the sleeve 22 at the time point when the supply of the molten metal into the sleeve 22 is completed becomes preferably 70% or more and more preferably 80% or more. Further, the molten metal supply control circuit 32b controls the electromagnetic pump 54 so that the filling rate of the molten metal in the sleeve 22 when the plunger tip 24a reaches a position of blocking the molten metal supply port 28 becomes preferably 95% or more and more preferably 98% or more. Entrainment of gas in the molten metal is reduced, and the quality of the die casting product is improved.

Further, in the die casting machine 100 of the first embodiment, the injection control circuit 32c controls the injection drive device 25 so that the injection speed of the plunger 24 increases after the plunger tip 24a reaches a position of blocking the molten metal supply port 28. Therefore, it is possible to shorten the manufacturing time of the die casting product.

As described above, according to the first embodiment, since the actuator 90 which reduces the pushing force of the molten metal supply pipe 40 with respect to the sleeve 22 when the plunger 24 is sliding is provided, an impact which is applied to the molten metal supply pipe 40 during the injection of the plunger 24 is reduced. Thus, it is possible to realize the die casting machine capable of suppressing the breakage of the molten metal supply pipe 40.

Second Embodiment

A die casting machine of a second embodiment is different from that of the first embodiment in that a molten metal supply pipe is movable relative to a holding furnace and a pushing force variable mechanism changes a force applied to the molten metal supply pipe independently from the holding furnace. Hereinafter, some descriptions of the contents overlapping with the first embodiment will be omitted.

FIG. 8 is a schematic cross-sectional view showing a sleeve, a plunger, and a molten metal supply device of the die casting machine of the second embodiment.

12

The die casting machine of the second embodiment is a semi-hot chamber type die casting machine.

The die casting machine of the second embodiment includes a mold clamping device 10, an extrusion device 12, 5 an injection device 14, a mold 16, a control system 18, and a molten metal supply device 20.

The injection device 14 includes a sleeve 22, a plunger 24, an injection drive device 25, and a position sensor 27. The plunger 24 includes a plunger tip 24a and a plunger rod 24b. 10 The sleeve 22 is provided with a molten metal sensor 26 (first sensor), a molten metal supply port 28, and a gas vent port 30.

The mold 16 includes a fixed die 16a and a movable die 16b.

15 The control system 18 includes a control device 32, an input device 34, and a display device 36. The control device 32 includes a molding condition setting circuit 32a, a molten metal supply control circuit 32b, an injection control circuit 32c, and a pushing force control circuit 32d.

20 The molten metal supply device 20 includes a molten metal supply pipe 40, a holding furnace 42, a packing 44, a first heater 46, a molten metal supply pipe sleeve 50, a second heater 52, an electromagnetic pump 54 (molten metal supply drive device), a molten metal level sensor 56 (second sensor), a metal feeder 64, a molten metal supply pipe support member 80, an actuator 82 (pushing force variable mechanism), an actuator support member 84, an elastic body 85, and a slide member 86. The holding furnace 42 is provided with a holding furnace molten metal level 25 sensor 66, a filter 68, a filter support 70, a holding furnace heater 72, and a metal supply port 74. The electromagnetic pump 54 includes a coil 54a and a core 54b.

25 The molten metal supply pipe 40 is provided below the sleeve 22. One end of the molten metal supply pipe 40 is pushed against the sleeve 22 to cover the molten metal supply port 28. The molten metal supply pipe 40 contacts the sleeve 22 so that the center axis of the molten metal supply pipe 40 is aligned to the center axis of the molten metal supply port 28.

30 40 A pushing force of the molten metal supply pipe 40 with respect to the sleeve 22 is variable. The pushing force of the molten metal supply pipe 40 with respect to the sleeve 22 is adjusted by the actuator 82. The molten metal supply pipe 40 is relatively movable, for example, with respect to the holding furnace 42. The molten metal supply pipe 40 has a function of supplying the molten metal into the sleeve 22.

35 50 The molten metal supply pipe support member 80 has a function of supporting the molten metal supply pipe 40. The molten metal supply pipe support member 80 supports the molten metal supply pipe 40 with a fringe provided at the upper end of the molten metal supply pipe 40.

55 60 The actuator 82 is an example of a pushing force variable mechanism. The actuator 82 moves the molten metal supply pipe 40 in the up and down direction. The actuator 82 has a function of reducing the pushing force of the molten metal supply pipe 40 against the sleeve 22 when the plunger 24 is sliding. The actuator 82 changes a force applied to the molten metal supply pipe 40 independently from the holding furnace 42.

65 60 The actuator 82 is, for example, a pneumatic cylinder. The actuator 82 may be, for example, a hydraulic cylinder or a solenoid actuator.

The actuator support member 84 supports the actuator 82. The molten metal supply pipe 40 and the molten metal supply pipe sleeve 50 move relative to each other in the up and down direction by operating the actuator 82. Further, the molten metal supply pipe support member 80 and the

13

actuator support member 84 move relative to each other in the up and down direction by operating the actuator 82.

The elastic body 85 is provided between the molten metal supply pipe support member 80 and the actuator support member 84. The elastic body 85 applies a pushing force for the sleeve 22 to the molten metal supply pipe 40.

From the viewpoint of stabilizing the pushing force of the molten metal supply pipe 40 with respect to the sleeve 22, for example, each of the actuator 82 and the elastic body 85 is disposed at three or more positions around the molten metal supply pipe 40.

The slide member 86 is provided between the molten metal supply pipe 40 and the molten metal supply pipe sleeve 50. The slide member 86 suppresses the molten metal from leaking from a gap between the molten metal supply pipe 40 and the molten metal supply pipe sleeve 50.

When starting the supply of the molten metal, the pushing force control circuit 32d controls the actuator 82 so that the pushing force of the molten metal supply pipe 40 with respect to the sleeve 22 becomes the sum of the force f which is applied to the molten metal supply pipe support member 80 by the elastic body 85 and the force F in which the actuator 82 pushes up the molten metal supply pipe support member 80.

The pushing force control circuit 32d has a function of controlling the actuator 82 based on the position of the plunger 24 detected by the position sensor 27. For example, the pushing force control circuit 32d reduces the pushing force of the molten metal supply pipe 40 with respect to the sleeve 22 by controlling the actuator 82 after the plunger tip 24a blocks the molten metal supply port 28. Specifically, for example, the application of the force by the actuator 82 is stopped. The actuator 82 changes the force applied to the molten metal supply pipe 40 independently from the holding furnace 42.

As described above, according to the second embodiment, since the actuator 82 which reduces the pushing force of the molten metal supply pipe 40 with respect to the sleeve 22 when the plunger 24 is sliding is provided, it is possible to realize the die casting machine capable of reducing the impact applied to the molten metal supply pipe 40 during the injection of the plunger 24 and suppressing the breakage of the molten metal supply pipe 40.

Further, the second embodiment is different from the first embodiment in that only the molten metal supply pipe 40 is independently moved up and down. In other words, the holding furnace 42 is fixed. Thus, the second embodiment is suitable for a large die casting machine that requires a heavy holding furnace 42.

Third Embodiment

A die casting machine of a third embodiment is different from that of the first embodiment in that a molten metal supply drive device is a pneumatic device that raises an air pressure in a holding furnace. Hereinafter, some descriptions of the contents overlapping with the first embodiment will be omitted.

FIG. 9 is a schematic cross-sectional view showing a sleeve, a plunger, and a molten metal supply device of the die casting machine of the third embodiment.

The die casting machine of the third embodiment is a semi-hot chamber type die casting machine.

The die casting machine of the third embodiment includes a mold clamping device 10, an extrusion device 12, an injection device 14, a mold 16, a control system 18, and a molten metal supply device 20.

14

The injection device 14 includes a sleeve 22, a plunger 24, an injection drive device 25, and a position sensor 27. The plunger 24 includes a plunger tip 24a and a plunger rod 24b. The sleeve 22 is provided with a molten metal sensor 26 (first sensor), a molten metal supply port 28, and a gas vent port 30.

The mold 16 includes a fixed die 16a and a movable die 16b.

The control system 18 includes a control device 32, an input device 34, and a display device 36. The control device 32 includes a molding condition setting circuit 32a, a molten metal supply control circuit 32b, an injection control circuit 32c, and a pushing force control circuit 32d.

The molten metal supply device 20 includes a molten metal supply pipe 40, a holding furnace 42, a packing 44, a first heater 46, a guard member 48, a molten metal supply pipe sleeve 50, a second heater 52, a pneumatic device 88 (molten metal supply drive device), a molten metal level sensor 56 (second sensor), a fulcrum 62, an actuator 90 (pushing force variable mechanism), an elastic body 92, a push-up member 94, a load sensor 96, and a stopper 98. The holding furnace 42 is provided with a holding furnace molten metal level sensor 66, a filter 68, a filter support 70, and a holding furnace heater 72.

The pneumatic device 88 generates a driving force for transferring the molten metal from the holding furnace 42 to the sleeve 22 via the molten metal supply pipe 40. The pneumatic device 88 pressurizes the inside of the holding furnace 42 by supplying a gas into the closed holding furnace 42. Accordingly, a pressure which is higher than an atmospheric pressure is applied to the molten metal surface in the holding furnace 42. Due to this pressure, the sleeve 22 is filled with the molten metal.

The molten metal supply control circuit 32b has a function of controlling the supply of the molten metal from the holding furnace 42 into the sleeve 22 based on the data of the molten metal surface position detected by the molten metal sensor 26 and the molten metal level sensor 56. The supply of the molten metal into the sleeve 22 is performed by controlling the driving of the pneumatic device 88.

As described above, according to the third embodiment, since the actuator 90 which reduces the pushing force of the molten metal supply pipe 40 with respect to the sleeve 22 when the plunger 24 is sliding is provided, the impact applied to the molten metal supply pipe 40 during the injection of the plunger 24 is reduced. Thus, it is possible to realize the die casting machine capable of suppressing the breakage of the molten metal supply pipe 40.

50

Fourth Embodiment

A die casting machine of a fourth embodiment is different from that of the third embodiment in that a molten metal supply pipe is movable relative to a holding furnace and a pushing force variable mechanism changes a force applied to the molten metal supply pipe independently from the holding furnace. Hereinafter, some descriptions of the contents overlapping with the first embodiment and the third embodiment will be omitted.

FIG. 10 is a schematic cross-sectional view showing a sleeve, a plunger, and a molten metal supply device of the die casting machine of the fourth embodiment.

The die casting machine of the fourth embodiment is a semi-hot chamber type die casting machine.

The die casting machine of the fourth embodiment includes a mold clamping device 10, an extrusion device 12,

15

an injection device 14, a mold 16, a control system 18, and a molten metal supply device 20.

The injection device 14 includes a sleeve 22, a plunger 24, an injection drive device 25, and a position sensor 27. The plunger 24 includes a plunger tip 24a and a plunger rod 24b. The sleeve 22 is provided with a molten metal sensor 26 (first sensor), a molten metal supply port 28, and a gas vent port 30.

The mold 16 includes a fixed die 16a and a movable die 16b.

The control system 18 includes a control device 32, an input device 34, and a display device 36. The control device 32 includes a molding condition setting circuit 32a, a molten metal supply control circuit 32b, an injection control circuit 32c, and a pushing force control circuit 32d.

The molten metal supply device 20 includes a molten metal supply pipe 40, a holding furnace 42, a packing 44, a first heater 46, a molten metal supply pipe sleeve 50, a second heater 52, a pneumatic device 88 (molten metal supply drive device), a molten metal level sensor 56 (second sensor), a molten metal supply pipe support member 80, an actuator 82 (pushing force variable mechanism), an actuator support member 84, a slide member 86, and a stopper 98. The holding furnace 42 is provided with a holding furnace molten metal level sensor 66, a filter 68, a filter support 70, a holding furnace heater 72, and a metal supply port 74.

The molten metal supply pipe 40 is provided below the sleeve 22. One end of the molten metal supply pipe 40 is pushed against the sleeve 22 to cover the molten metal supply port 28. The molten metal supply pipe 40 contacts the sleeve 22 so that the center axis of the molten metal supply pipe 40 is aligned to the center axis of the molten metal supply port 28.

The pushing force of the molten metal supply pipe 40 with respect to the sleeve 22 is variable. The pushing force of the molten metal supply pipe 40 with respect to the sleeve 22 is adjusted by the actuator 82. For example, the molten metal supply pipe 40 is movable relative to the holding furnace 42. The molten metal supply pipe 40 has a function of supplying the molten metal into the sleeve 22.

The molten metal supply pipe support member 80 has a function of supporting the molten metal supply pipe 40. The molten metal supply pipe support member 80 supports the molten metal supply pipe 40 with a fringe provided at the upper end of the molten metal supply pipe 40.

The actuator 82 is an example of a pushing force variable mechanism. The actuator 82 moves the molten metal supply pipe 40 in the up and down direction. The actuator 82 has a function of reducing the pushing force of the molten metal supply pipe 40 with respect to the sleeve 22 when the plunger 24 is sliding.

The actuator 82 is, for example, a pneumatic cylinder. The actuator 82 may be, for example, a hydraulic cylinder or a solenoid actuator.

The actuator support member 84 supports the actuator 82.

The molten metal supply pipe 40 and the molten metal supply pipe sleeve 50 move relative to each other in the up and down direction by operating the actuator 82. Further, the molten metal supply pipe support member 80 and the actuator support member 84 move relative to each other in the up and down direction by operating the actuator 82.

The elastic body 85 is provided between the molten metal supply pipe support member 80 and the actuator support member 84. The elastic body 85 applies a pushing force for the sleeve 22 to the molten metal supply pipe 40.

From the viewpoint of stabilizing the pushing force of the molten metal supply pipe 40 with respect to the sleeve 22,

16

for example, each of the actuator 82 and the elastic body 85 is disposed at three or more positions around the molten metal supply pipe 40.

The slide member 86 is provided between the molten metal supply pipe 40 and the molten metal supply pipe sleeve 50. The slide member 86 suppresses the molten metal from leaking from a gap between the molten metal supply pipe 40 and the molten metal supply pipe sleeve 50.

The stopper 98 is provided above the molten metal supply pipe support member 80. The stopper 98 limits the upward displacement of the molten metal supply pipe support member 80 and suppresses the excessive pushing force of the molten metal supply pipe 40 with respect to the sleeve 22.

When starting the supply of the molten metal, the pushing force control circuit 32d controls the actuator 82 so that the pushing force of the molten metal supply pipe 40 with respect to the sleeve 22 becomes the sum of the force f which is applied to the molten metal supply pipe support member 80 by the elastic body 85 and the force F in which the actuator 82 pushes up the molten metal supply pipe support member 80.

The pushing force control circuit 32d has a function of controlling the actuator 82 based on the position of the plunger 24 detected by the position sensor 27. For example, the pushing force control circuit 32d reduces the pushing force of the molten metal supply pipe 40 with respect to the sleeve 22 by controlling the actuator 82 after the plunger tip 24a blocks the molten metal supply port 28. Specifically, for example, the application of the force by the actuator 82 is stopped. The actuator 82 changes the force applied to the molten metal supply pipe 40 independently from the holding furnace 42.

As described above, according to the fourth embodiment, since the actuator 82 which reduces the pushing force of the molten metal supply pipe 40 with respect to the sleeve 22 when the plunger 24 is sliding is provided, it is possible to realize the die casting machine capable of reducing the impact applied to the molten metal supply pipe 40 during the injection of the plunger 24 and suppressing the breakage of the molten metal supply pipe 40.

Further, in the fourth embodiment, only the molten metal supply pipe 40 is moved up and down unlike the third embodiment. In other words, the holding furnace 42 is fixed. Thus, the fourth embodiment is suitable for a large die casting machine that requires a heavy holding furnace 42.

The embodiments of the invention have been described above with reference to specific examples. However, the invention is not limited to these specific examples. In the embodiments, the description of the part of the die casting machine or the like that is not directly required for the description of the invention is omitted, but the required elements related to the die casting machine or the like can be appropriately selected and used.

It is also possible to provide a horizontal moving means that enables horizontal movement of the holding furnace 42 below the holding furnace 42 of the first to fourth embodiments. The horizontal moving means is, for example, a vehicle wheel. The maintenance of the holding furnace 42 becomes easy by providing the horizontal moving means.

In addition, all die casting machines which include the elements of the invention and which can be appropriately redesigned by those skilled in the art are included in the scope of the invention. The scope of the invention is defined by the scope of claims and the scope of their equivalents.

What is claimed is:

1. A die casting machine comprising:
a holding furnace configured to hold molten metal;
a sleeve located outside the holding furnace, the sleeve connected to an inside of a mold, and the sleeve including a molten metal supply port;
a plunger configured to slide through the sleeve and including a plunger rod and a plunger tip fixed to a tip of the plunger rod;
a molten metal supply pipe pushed against the sleeve to cover the molten metal supply port and configured to supply the molten metal into the sleeve;
a pushing force variable mechanism configured to reduce a pushing force of the molten metal supply pipe against the sleeve when the plunger is sliding; and
a first sensor facing a predetermined height between a lowermost portion and an uppermost portion of an inner surface of the sleeve and configured to detect that the molten metal in the sleeve reaches the predetermined height.
2. The die casting machine according to claim 1, further comprising:
an injection drive device configured to drive the plunger; and
an injection control circuit configured to control the injection drive device so that an injection speed of the plunger increases after the plunger tip reaches a position of blocking the molten metal supply port.
3. The die casting machine according to claim 1, further comprising:
a pushing force control circuit configured to reduce the pushing force by controlling the pushing force variable mechanism after the plunger tip blocks the molten metal supply port.
4. The die casting machine according to claim 1, wherein the molten metal supply port is provided at a lower portion of the sleeve.
5. The die casting machine according to claim 1, wherein the molten metal supply pipe is fixed to the holding furnace and the pushing force variable mechanism changes a force applied to the holding furnace.
6. The die casting machine according to claim 1, wherein the molten metal supply pipe is movable relative to the holding furnace and the pushing force variable mechanism changes a force applied to the molten metal supply pipe independently from the holding furnace.
7. The die casting machine according to claim 1, wherein the molten metal supply pipe has a cylindrical shape extending in a linear shape.

8. The die casting machine according to claim 7, wherein the molten metal supply pipe is made of ceramics.
9. The die casting machine according to claim 1, further comprising:
a molten metal supply drive device configured to generate a driving force for transferring the molten metal from the holding furnace to the sleeve via the molten metal supply pipe.
10. The die casting machine according to claim 9, wherein the molten metal supply drive device is an electromagnetic pump.
11. The die casting machine according to claim 9, wherein the molten metal supply drive device is a pneumatic device raising an air pressure in the holding furnace.
12. The die casting machine according to claim 9, further comprising:
a molten metal supply control circuit configured to control the molten metal supply drive device so that a filling rate of the molten metal in the sleeve becomes 70% or more at a time point when a supply of the molten metal into the sleeve is completed and configured to control the molten metal supply drive device so that a filling rate of the molten metal in the sleeve becomes 95% or more when the plunger tip reaches a position of blocking the molten metal supply port.
13. A die casting machine comprising:
a holding furnace configured to hold molten metal;
a sleeve located outside the holding furnace, the sleeve connected to an inside of a mold, and the sleeve including a molten metal supply port;
a plunger configured to slide through the sleeve and including a plunger rod and a plunger tip fixed to a tip of the plunger rod;
a molten metal supply pipe pushed against the sleeve to cover the molten metal supply port and configured to supply the molten metal into the sleeve; and
a pushing force variable mechanism configured to reduce a pushing force of the molten metal supply pipe against the sleeve when the plunger is sliding;
wherein the sleeve includes a gas vent port provided at an upper portion, and wherein the die casting machine further comprises a second sensor provided above the gas vent port and configured to supply a molten metal surface position of the molten metal in the sleeve.
